(57) **CLAIM**

The ornamental design of fork with joined shank, as shown
and described.

DESCRIPTION

FIG. 1 is a perspective view showing our new fork with
joined shank;

FIG. 2 is a front elevational view thereof;

FIG. 3 is a rear elevational view thereof;

FIG. 4 is a top plan view thereof;

FIG. 5 is a right elevational side view thereof, the left side
elevational view thereof being a mirror image of that which
is shown; and,

FIG. 6 is a bottom plan view thereof.
